[57] CLAIM

The ornamental design for a stuffed toy bee figure, as shown and described.

DESCRIPTION

FIG. 1 is a front elevation of a stuffed toy bee figure showing my new design;

FIG. 2 is a back elevation thereof;

FIG. 3 is a right side elevation thereof, the left side elevation being a mirror image of the right side elevation;

FIG. 4 is a top view thereof; and

FIG. 5 is a bottom view thereof.
